AUTOMOBILE HEATER

Henry J. De N. McCollum, Evanston, Ill.

Application April 6, 1938, Serial No. 200,312

2 Claims. (Cl. 237—12.3)

The invention relates generally to automobile heaters and the present application is a continuation in part of a co-pending application, Serial No. 61,213 filed January 28, 1936.

More particularly, the present invention relates to the operation and control of those engine-created vacuums which may be used as a source of power to provide the fluid pressure differential needed for the production and movement of a stream of hot gases through a radiator in the operation of the independent heat generator illustrated and described in said co-pending application.

In the particular embodiment illustrated, the vacuum which is utilized for the purposes mentioned is that which is developed in the intake manifold of the engine. However, it is appreciated that, with this particular source, the degree of vacuum created ranges from zero to approximately twenty-six inches of mercury, depending upon the speed and the load to which the engine is subjected under operating conditions. Under such circumstances, if the degree of vacuum applied to the heat generator to draw the combustible mixture and hot gases through the heater were permitted to vary likewise, it is apparent that the operation of the heater would be irregular and unsatisfactory.

Consequently, it is one of the objects of the present invention to convert the widely varying degree of vacuum created in the intake manifold of an automobile engine into a substantially uniform working vacuum for operating a combustion heat generator of the class described.

Another object of the invention is to provide an improved means for causing a substantially uniform rate of flow of the gases of combustion through the heater.

Another object of the invention is to provide a compensator which provides a gradual compensating correction for variations in the degree of vacuum in the intake manifold of an internal combustion engine.

Another object of the invention is to provide in a heater of the class described, a compensator therefor, which is simple in construction and operation, effective in use and inexpensive to manufacture and operate.

Another object of the invention is to provide a compensator for an internal combustion heater for regulating the pressure differential employed in the operation of the heater, which is fully adjustable throughout all vacuum differentials and easily disassembled for repair and maintenance.

These being among the objects of the inven-

tion, other and further objects will become apparent from the drawing herein, the description relating thereto, and the appended claims.

Referring now to the embodiment of the invention illustrated, partly in section, in the single view of the accompanying drawing, the heater construction 10, which is more particularly described in said co-pending application, comprises generally, a carbureting device 12 supplied with gasoline preferably from the float bowl 14 of the usual engine carburetor. Suitable means is provided to control the flow of gasoline to the heater 10 and the amount of air mixed therewith in order to supply to the heater several combustible mixtures of different degrees of richness to take care of the various heater requirements encountered under starting and running conditions.

The combustible mixture supplied by the carbureting device is fed into the combustion chamber 16 through a tube 18 and a perforated baffle 20 plate 20 by means of which preheat and turbulence are effected to thoroughly vaporize the mixture entering the combustion chamber. The mixture is ignited by an electrical heating element 22 located in a recess 24 in the side of the chamber, and, in event the flame ever becomes extinguished, the mixture is reignited by a refractory ceramic plug 26 at the outlet of the combustion chamber which acquires a sufficiently high temperature for such purpose by being directly exposed to the flame during the normal operation of the heater.

From the combustion chamber 16 the hot gases pass through a radiator 28 comprising a circuitous tube 30 to which heat radiating fins 32 are thermally connected. Over these fins air is circulated in a manner whereby heat is transferred from the hot gases to the passenger compartment of the automobile for the comfort of the passengers.

The flow of gases through the heater 10 is controlled in two ways: one, by the valve 36 which starts and stops the flow, and the other by a compensator 40 interposed between the heater 10 and the intake manifold for regulating and rendering uniform the degree of vacuum to which the heater is subjected.

In the particular embodiment of the compensator illustrated by enlargement in the accompanying drawing, a butterfly valve 42 is mounted within a pipe 44 connecting the heater 10 with the intake manifold to compensate for variations in intake manifold vacuum.

The stem 46 of the butterfly valve has an arm 48 secured thereto, the free end of the arm being

connected by link 50 to a piston 52 which is freely reciprocal in the cylinder 54. The cylinder is in communication with the pipe 44 through a relatively small port 56 and the piston is normally held in the position in which it is shown by a compression coil spring 58 whenever the vacuum differential ranges from zero to the degree necessary for the best operation of the heater. The lower end of the spring 58 rests upon a swivel 10 retainer 60 which is carried by an adjusting screw 62 so that the effectiveness of the butterfly valve 42 may be varied at will according to the different requirements which a user may seek to impose upon a heater such as that illustrated 15 and described herein.

When the intake manifold vacuum is of a normal value, the spring will offer sufficient resistance to the downward movement of the piston to hold the butterfly valve in its completely open 20 position as shown. When, however, the intake manifold exceeds that necessary for the best operation of the heater, the decrease in the pressure will be transmitted through the port 56 to the cylinder 54 beneath the piston 52 and the atmospheric pressure upon the top of the piston will 25 force the piston downwardly against the force of the spring 58, thus partially closing the butterfly valve 42 in direct relationship with the degree of pressure differential existing upon both sides of 30 the piston 52.

Partial closure of the valve 42 will of course result in decreasing the rate of flow of the gases of combustion from the heater and thereby compensate for such changes in the intake manifold 35 vacuum as from time to time will be experienced in engine performance. The port 56 is made sufficiently small that the opening and closing of the butterfly valve will be relatively gradual and will be free from fluttering.

40 In this way, a compensator which is simple in form and easily constructed, operated and maintained, is provided for an internal combustion heater which converts the widely varying degree of vacuum to which the heater might otherwise be directly subjected with a substantially uniform working vacuum for causing a substantially uniform rate of flow of the gases of combustion through the heater under gradually compensating corrections within the objects expressed and implied herein.

50 Consequently, although a single embodiment of the invention has been shown and described herein, it will be apparent to those skilled in the art that various and further uses, modifications and changes may be made without departing from 55 the spirit and substance of the invention, the

scope of which is commensurate to the appended claims.

What is claimed is:

1. In an automobile heater of the class described which utilizes vacuum developed in the intake manifold of the automobile engine, the combination comprising, means providing a combustion chamber, means for feeding fuel to the combustion chamber, a conduit connecting the combustion chamber to the intake manifold to effect a reduction of pressure within the combustion chamber, and means for compensating for variations in pressure in the intake manifold, the last mentioned means comprising a valve in said conduit, a casing providing a cylinder open at 10 one end and having an opening therein near the other end, means connecting the said opening in the casing to the conduit intermediate the said valve and the combustion chamber, a piston slid- 15 able in the cylinder and disposed between the open end thereof and said opening in the casing so as to be exposed to atmospheric pressure on one side and to pressure within a portion of the conduit on the other side, a spring biasing the piston toward the open end of the casing, and a 20 link connecting the piston to the valve in the conduit so that the valve is moved responsive to movements of the piston.

2. In an automobile heater of the class described which utilizes vacuum developed in the intake manifold of the automobile engine, the combination comprising, means providing a combustion chamber, means for feeding fuel to the combustion chamber, a conduit connecting the combustion chamber to the intake manifold to effect a reduction of pressure within the combustion chamber, a valve for shutting off the conduit, and means for compensating for variations in pressure in the intake manifold, the last mentioned means comprising a valve in said conduit, 30 a casing providing a cylinder open at one end and having an opening therein near the other end, means connecting the said opening in the casing to the conduit intermediate the said valve and the combustion chamber, a piston slid- 35 able in the cylinder and disposed between the open end thereof and said opening in the casing so as to be exposed to atmospheric pressure on one side and to pressure within a portion of the conduit on the other side, a spring biasing the piston toward the open end of the casing, and a link connecting the piston to the valve in the conduit so that the valve is moved responsive to movements of the piston. 40
